CLOTHESLINE

John H. Klamer and Ejnar Nyborg,
Brooklyn, N. Y.

Application December 9, 1933, Serial No. 701,584

8 Claims. (Cl. 68—3)

The purpose of this invention is to provide a clothes line of the type that may be reached thru a window in which a portion of the line may be drawn thru the window with the line in tension so that clothes may be hung upon or removed from the line from the interior and the entire line may be moved as a unit to the outside.

Many clothes lines of this type have been provided; however, it is necessary to reach out of the window to hang clothes on the line or slack the line in order to draw a portion of it thru the window and lines of these types are objectionable.

The object of the invention is, therefore, to provide means for supporting a clothes line in which the entire line may be moved as a unit and a portion thereof may extend on the inside of the window so that clothes or the like may be hung thereon or removed therefrom without releasing the line.

Another object is to provide means for attaching a guide line to a clothes line so that the pulley holding the outer end of the clothes line may readily move inward or outward while the line is in tension, and in which the tension may be adjusted.

With these ends in view, the invention embodies a bracket adapted to be attached to the side of a window frame, a bar slidable in said bracket and having a head pulley of a clothes line held on the inner end thereof, a tail pulley, a guide pulley adapted to be attached to a fixed object outside of the window, and a guide line attached to the outer end of said bar and passing around a pulley in said bracket and also around the guide pulley and with the outer end attached to the tail pulley, and suitable brackets for supporting said device.

Other features and advantages of the invention will appear from the following description taken in connection with the drawing, wherein:

Figure 1 is a view showing the device as it may appear in use.

Figure 2 is a view on a slightly larger scale, looking toward the opposite side of the device and showing an alternate design.

Figure 3 is a detail showing the inner end of the device in the design shown in Figure 2.

Figure 4 is a cross section thru the tubular bar.

Figure 5 is a plan view of the device.

Figure 6 is a cross section thru the inner end of the device on line 6—6 of Figure 3.

Figure 7 is a plan view similar to that shown in Figure 5 with parts omitted showing an al-

ternate arrangement in which means is provided for locking the device in the outward position.

In the drawing the device is shown as it would be made wherein numeral 1 indicates the tubular bar, numeral 2 the head pulley, and numeral 3 the tail pulley.

The bar 1 is preferably made of a tube having a slot 4 in one side and this bar is held upon rollers 5 and 6 which are pivotally mounted on a bar 7 and the bar 7 is rigidly held in an arm 8 which may be installed upon the outer surface of a window frame by a bracket 9 to which it is pivotally attached by a bolt 10 thru a hub 11 and a tongue 12 extending from the back of the bracket. A projection 13 may extend from one side of the bracket and this may have an opening 14 therein thru which a bolt or screw may be placed which will hold in the edge of the window frame, whereas the face of the bracket 9 may be held by bolts or screws 15 and 16 in the ends thereof.

It will be understood that this mounting is only typical as the device may be held in any other manner or any other means may be used for supporting the inner end thereof. It will be noted that the inner end of the bar 7 is pivotally attached to the arm 8 by a bolt 17 so that the angle thereof may be raised or lowered in order to adjust it to any position thereby making it possible for the clothes line to extend straight outward or to extend upward or downward. The arm 8 is also pivotally attached to the bracket 9 so that the horizontal angle may also be adjusted thereby making it possible for the device to extend straight outward from the window or to either side, and once the device is in position it may be held by a downwardly extending brace 18 and a lateral brace 19. These braces may be attached to the window frame or to the side of the building or to any surface against which the device may be held. The relative positions of the rollers 5 and 6 make it possible for the bar 1 to be supported at two points and these points are located a sufficient distance apart to support the bar in either the outer or inner position.

The head pulley 2 is mounted at the inner end of the bar 1 by a bracket 20 and the bracket may be provided with a knob 21 by which it may be gripped when it is desired to move it from one position to the other. The head pulley is pivotally mounted in the bracket 20 and the bracket may be provided with guards 22 and 23 which extend over the upper and lower edges in order to hold the clothes line in place. A small pulley 24 is also rotatably mounted on a pin 25 in the arm 8 at this end of the device and the guide line 26

is attached to the outer end of the bar 1 and passes around the head pulley 2 and the small pulley 24 and then around the tail pulley 3 and the guide pulley 27 and is attached to the outer end of the bar 1.

The tail pulley 3 is mounted on the outer end of the bar 1 by a bracket 28 and the bracket may be provided with a knob 29 by which it may be gripped when it is desired to move it from one position to the other. The tail pulley is pivotally mounted in the bracket 28 and the bracket may be provided with guards 30 and 31 which extend over the upper and lower edges in order to hold the clothes line in place.

The guide pulley 27 is mounted on the outer end of the bar 1 by a bracket 32 and the bracket may be provided with a knob 33 by which it may be gripped when it is desired to move it from one position to the other. The guide pulley is pivotally mounted in the bracket 32 and the bracket may be provided with guards 34 and 35 which extend over the upper and lower edges in order to hold the clothes line in place. A small pulley 36 is also rotatably mounted on a pin 37 in the arm 8 at this end of the device and the guide line 26

is attached to the outer end of the bar 1 and passes around the tail pulley 3 and the small pulley 36 and then around the head pulley 2 and the small pulley 24 and is attached to the outer end of the bar 1.

extends over this pulley, as shown in Figure 2. The inner end of the guide line is held to a projection 27 at the outer end of the bar 1 by a thumb screw 28 and it will be noted that this 5 thumb screw may be tightened or loosened to hold the guide line and by taking up the line at this point it is possible to take up slack in the guide line and thereby take up slack in the entire clothes line so that the clothes line may be kept in tension. From the pulley 24 the guide line 26 extends 10 outward over another pulley 29 which may be held to a post or other fixed object located at some distance from the window and after passing around this pulley the guide line is attached to 15 the bracket 30 of the tail pulley 3 at the point 31. The pulley 29 may be provided with a guard 32 by which it may be held by a cord 33 or by any other means to the fixed object and the bracket or guard 30 is provided with an upper extension having a 20 roller 34 positioned therein to ride upon the guide line 26 thereby holding the tail pulley 3 in the upright position.

The guide line may also be provided as shown in Figure 1 in which an additional pulley 35 is 25 provided above the pulley 29 and another pulley 36 is provided above the pulley 24 thereby making it possible to raise the elevation of the guide line so that it is a sufficient distance above the clothes 30 to prevent them wrapping around the guide line as they are blown by the wind. In this design the extension on the bracket 30 of the tail pulley 3 may also be extended upward and provided with a roller 37 so that it may roll upon the guide line. It will be appreciated that any other means may 35 be provided for holding the guide line or for separating it from the clothes line at any point or points.

It will be noted that the device may be mounted 40 upon the outside of a window frame and positioned just below the upper sash and normally the entire device will extend outward with the tail pulley held outward by the guide line. When it is desired to hang clothes upon the device the clothes line, which is indicated by the numeral 45 38, may be drawn inward by drawing in the bar 1 by the handle 21 and as this is drawn inward, the head and tail pulleys 2 and 3 will move inward to their respective positions indicated by the dotted lines 39 and 40 so that the head pulley will be 50 considerably inside of the window and clothes may be hung thereon or removed therefrom. Any type of line may be used and the pulley may be of any size or mounted or arranged in any manner.

The device may also be made, as shown in Figure 7, in which the pulley 2 is mounted upon a pin 41 in a yoke 42 at the end of the bar 1 and the head 43 of the pin snaps into a slot 44 of a member 45 which may be attached to the bar 7 and which extends downward therefrom. A spring 46 is provided between the head 43 and the side of the yoke and the opposite end 47 of the pin is held in a handle 48 having projections 49 thereon and it will be noted that as the handle is 55 twisted to either side, it will draw the pin 41 thru the yoke, compressing the spring and drawing the head out of the slot 44 so that the device may be released and pulled inward; and when the device is moved outward, the head 43 will engage the bevelled surface 50 and slide upward so that it will snap into the slot.

The construction will be readily understood from the foregoing description. In use the device may be installed as hereinbefore described and clothes may be placed on the line or removed 75

therefrom by drawing the head pulley inward and it will be noted that as the head pulley is drawn inward with the rod 1, the guide line 26 will move outward as one end thereof is attached to the outer end of the rod 1 and the other to the tail pulley 3 so that as the rod 1 moves inward the tail pulley will also move inward a similar amount thereby maintaining a constant length of the guide line 26. The device, therefore, makes it possible to move the end of a clothes line in 10 thru a window while the line is held in tension and constant tension may be maintained by taking up the length of the guide line thru the thumb screw 28 at the outer end of the rod 1, and after the clothes have been placed upon or removed 15 from the line it is only necessary to take hold of the knob and move the entire line back out of the window and to the outside or drying position.

In the design shown in Figures 1 and 2 the device is shown attached to the outside of a 20 window frame and the dotted lines indicate the position of the inner end of the device when it is drawn inward inside of the window. The clothes may be placed upon the lower side of the clothes line, as indicated by the dotted lines, 25 and as the clothes are placed thereon this line may be moved until the complete lower strand is full. The line is free to rotate about the head and tail pulleys as it is independent of the guide line and, therefore, may move with the pulleys in any position.

Having thus fully described the invention what we claim as new and desire to secure by Letters Patent, is:

1. A clothes line comprising a continuous line, 35 head and tail pulleys upon which said line is mounted, a bracket adapted to be attached to the outside of a window frame, an arm slidably in said bracket and upon which the head pulley of said clothes line is mounted, and an auxiliary 40 guide line attached to a pulley block at the outer end of the clothes line in which said tail pulley is mounted and passing over a fixed pulley beyond the outer end thereof and also over a fixed pulley 45 at the inner end thereof, with the inner end attached to the slidable arm at a point between the pulley at the inner end of the clothes line and the pulley at the outer end for holding the line in tension.

2. In combination, a continuous clothes line 50 having head and tail pulleys, means mounting said tail pulley, a bracket attachable to the outside of a window frame, means slidably mounting the head pulley of said clothes line in said bracket, and a guide line with the ends attached to said head and tail pulley mounting means with the inner end attached at a point between said head and tail pulleys, said guide line passing over fixed outer and inner pulleys and adapted to hold said tail pulley outward with continuous tension as the line is moved, said head pulley mounting means adapted to permit the head end of said clothes line to be moved thru the window.

3. A combination as described in claim 2 having 55 means in said bracket for adjusting the angle of said head pulley mounting means to compensate for raising and lowering the outer end of the clothes line.

4. A combination as described in claim 2 in 60 which the end of the guide line is attached to the head pulley mounting means by a thumb screw whereby the length of the guide line may readily be changed to adjust the tension of said clothes line.

5. A combination as described in claim 2 having 65

means holding said guide line above said clothes line with the tail pulley of the clothes line supported therefrom.

6. A combination as described in claim 2 in which the head pulley mounting means comprises a tubular bar, mounted on rollers on a support extending from said bracket.

7. A clothes line as described in claim 1 having

a spring latch in the inner end of said arm engaging a recess in said bracket adapted to hold the arm in the outer position.

8. A combination as described in claim 2 having a spring latch for locking said head pulley mounting means in the outer position.
